UNITED STATES PATENT OFFICE.

FRANK D. INFANTINO, OF ROXBURY, MASSACHUSETTS.

DESIGN FOR A TUB AND SINK COMBINATION.

45,995.

Specification for Design.

Patented June 23, 1914.

Application filed March 12, 1914. Serial No. 824,320. Term of patent 7 years.

To all whom it may concern:

Be it known that I, FRANK D. INFANTINO, a citizen of the United States, residing at Roxbury, in the county of Suffolk and Commonwealth of Massachusetts, have invented a new, original, and ornamental Design for a Tub and Sink Combination, of which the following is a specification, reference being had to the accompanying drawing, forming a part thereof.

The figure is a perspective view of a tub and sink combination showing my new design.

I claim:

The ornamental design for a tub and sink combination as shown.

FRANK D. INFANTINO.

Witnesses:

CLYDE L. ROGERS,

EDWARD B. BROWN.
